UNITED STATES PATENT OFFICE.

WILLIAM GREEN, OF CHICAGO, ILLINOIS.

IMPROVEMENT IN SHEET-METAL-CAN FORMING MACHINES.

Specification forming part of Letters Patent No. 173,120, dated February 8, 1876; application filed August 30, 1875.

To all whom it may concern:

Be it known that I, WILLIAM GREEN, of Chicago, in the county of Cook and State of Illinois, have invented certain new and useful Improvements in Sheet-Metal-Can Forming Machines; and I do hereby declare the following to be a full, clear, and exact description thereof, which will enable others skilled in the art to which it appertains to make and use the same, reference being had to the accompanying drawing, forming part of this specification, in which—

Figure 1 is a longitudinal central section of a can-forming machine embodying my said invention. Fig. 2 is a top view of a portion of the same, showing the position of the forming-dies when opened to receive the blank. Figs. 3 and 4 are detached sections of the forming-dies. Fig. 5 is a diminished view of the end of a can when formed, showing the flanges at the top or bottom of the can-body. Fig. 6 is a transverse section of the forming-dies, taken on the line $x x$, drawn across Fig. 2, showing the position of the dies when folded. Fig. 7 is a modified form of dies used in forming cans having round corners.

Similar letters of reference indicate like parts in the several figures of the drawing.

My invention relates to that class of machines employed in forming the body of sheet-metal cans to be hermetically sealed; and its object is to so arrange the dies as to form the body of the can from one piece of metal, bringing the seam at the corner, and at the same time bending the edges of the top and bottom of each side of the body inward at a right angle to the plane of the sides, forming flanges to support the edges of the top and bottom of the can when soldered in place. To that end it consists in the several parts, as will be more fully understood by the following description and claims.

In the drawing, A represents the frame-work for supporting the operating parts of the machine. B is the forming-block, which is mounted on a horizontal arm, C, pivoted to a vertical upright, C', permanently attached to the bed A' of the frame. This arm is loosely secured between vertical guides or ways D D, and is so arranged as to admit of a free and easy tilting movement. E is the treadle, hinged

at its rear end to the frame A, and attached, near its forward end, to the arm C by a connecting-rod, d, as shown in Fig. 1. F is a coiled spring, located between the guides or ways D D under arm C, between it and the bed A'. The adjustment of this spring is such as to yield and allow the arm to descend when power is applied to the treadle, and to force the arm upward to its normal position when power is removed from the treadle. The forming-block B is made in any desired shape approximating the shape of the can-body to be formed. G G' and H H' are the forming-dies, which are hinged one to the other, and are permanently attached to bed A' in such a manner as to admit of being clamped or folded around the forming-block when the latter is depressed, as shown in Fig. 6. The outer edge of die-block H' is rabbeted on its face, forming a groove, C, so as to fit the face of lip d' when the die-blocks are folded around the forming-block, the object of which is to bend the edge of the blank to receive the opposite edge, forming the seam. Permanently attached to the outer edge of die-block G is a lip, d', arranged at a right angle to the face of the block, and adapted to lap over the corner of the forming-block when the die-block is folded against the side of the same. Permanently attached to the face of each die-block, across each end of the same, are gage-blocks J J, as shown in Fig. 2. These gage-blocks are each rabbeted on their inner adjacent faces, forming grooves f f, adapted to receive the edges of the blank. The ends of these gage-blocks proper are cut on an angle of forty-five degrees to the plane of the face, so that when the die-blocks are clamped around the forming-block the ends of the gage-blocks miter together, as shown in Fig. 6. The ends of the rabbeted edge of the gage-blocks on the die-blocks G G' are beveled inward toward the center at an angle of about forty-five degrees to the plane of the face and edge, as shown in Fig. 2. The length of the gage-blocks proper on the die-blocks H and H' is slightly less than the gross width of their respective die-blocks, and the gross length of the rabbeted edge is equal to the width of the block, as shown at e e, Fig. 2, and are chamfered or beveled at each end toward the bevel on the end of the gage-block proper at an an-

gle of about forty-five degrees, as shown at *h h*, Fig. 2, so that when the die-blocks are clamped around the forming-block the ends of the rabbeted edges of the gage-blocks miter together. The object of beveling the ends of the rabbeted edges of the gage-blocks, as described, is to insure room for the surplus metal at the corners of the can, produced by the bending of the flanges at the top and bottom of the can-body, and at the same time compress the surplus metal together, so as to fold it in line nearly parallel with the corners of the can-body, thus enabling it to be easily lapped over and hammered down without breaking. *K*, *K*, and *L* are handles permanently attached to the die-blocks *G*, *G'*, and *H'*, for operating the same.

The operation of my invention is as follows: The blank from which the can-body is to be formed is first cut in proper shape and of the proper size. The die-blocks being opened so as to be in one and the same plane, as shown in Fig. 2, and the blank placed upon them, allowing its edges to rest within the grooves *f f*, power is then applied to the treadle, imparting a downward movement to the forming-block, impinging the blank against die-block *H*, bending the edges of the blank resting within the grooves upward to a right angle with the plane of the face of the die-block, forming flanges against which the top and bottom are supported. The operator then folds die-block *G* against the side of the forming-block, bringing lip *d'* against the edge of the blank, bending the same over the corner of the forming-block, forming the lap for the seam, and at the same time bending the edges of the blank resting in the grooves over the end of the forming-block. Die-blocks *G'* and *H'* are then folded around the forming-block, impinging the blank against the sides of the forming-block, and bending the edges resting within the grooves

of the respective gage-blocks over the ends of the forming-block, and at the same time compressing the surplus metal at the corners of the flanges between the beveled ends of the rabbeted edge of the gage-blocks, folding the surplus metal in the form as shown in Fig. 5. The can-body is then removed from the machine, and the surplus metal at the corners bent downward upon the flange, and the top and bottom inserted and soldered to the flanges. In manufacturing cans having round corners the corners of the forming-block are made round, and the die-blocks concaved to fit them, as shown in Fig. 7.

I am aware that hinged lips have been used for making the final fold in cans; also, gage-blocks with beveled corner-folders with stationary die-blocks, and I do not, broadly, claim such devices; but

Having thus described my invention, I claim—

1. In combination with the forming block *B*, the hinged die-blocks *G* *G'* and *H* *H'*, die-block *G* provided with fixed lip *d'*, adapted to bend the edge of the blank over the corner of the forming-block, whereby the seam is formed at the corner of the can-body, as specified.

2. In combination with the hinged die-blocks, the gage-blocks *J* *J*, rabbeted to receive the edges of the blank, and adapted to bend the same against the end of the forming-block, forming the flanges at the top and bottom of the can-body, as specified.

3. The forming-block *B*, hinged die-blocks *G* *G'* and *H* *H'*, and lip *d*, in combination with the gage-blocks *J* *J*, beveled at the ends, all constructed as and for the purpose set forth.

WILLIAM GREEN.
